UNITED STATES PATENT OFFICE.

SAMUEL B. WILLIAMS, OF BROOKLYN, AND EDWARD E. HINRICHSEN, OF NEW YORK,
N. Y., ASSIGNEES TO WESTERN ELECTRIC COMPANY, INCORPORATED, OF NEW
YORK, N. Y., A CORPORATION OF NEW YORK.

TELEPHONE-EXCHANGE SYSTEM.

Application filed April 30, 1923. Serial No. 635,421.

To all whom it may concern:

Be it known that we, SAMUEL B. WILLIAMS and EDWARD E. HINRICHSEN, citizens of the United States of America, residing at 5 Brooklyn, in the county of Kings, and New York city, in the county of New York and State of New York, respectively, have invented certain new and useful Improvements 10 in Telephone Exchange Systems, of which the following is a full, clear, concise, and exact description.

This invention relates to telephone systems employing automatic switching apparatus for the establishment of connections.

15 The object of this invention is to enable an increase in the capacity of groups of lines or trunks, such as those leading to branch exchanges, without disturbing existing equipment and to otherwise improve the 20 service provided for said exchanges.

A feature of the invention relates to a system wherein, when a connection is built up to a particular group of lines, the established connection is partially released and 25 is automatically reestablished to a given one of the lines in the group.

Another feature relates to means, in a system having the lines of a group appearing in one or more switches with provision 30 for building a connection through to one of said switches, whereby when the connection is intended for said group it is temporarily released and automatically reestablished to an idle one of said lines in what- 35 ever switch it may appear.

Other features and advantages contemplated by the invention will be taken up in detail hereinafter and pointed out in the appended claims.

40 Considering the drawing, Figs. 1 to 13, inclusive, taken in the order illustrated in Fig. 14 disclose the details of a telephone system incorporating the features of the present invention.

45 Fig. 1 illustrates a line switch of the coordinate type in which the subscribers' lines terminate and also two of a number of trunks outgoing to a district selector switch.

50 Fig. 2 shows the controlling elements associated with one of the outgoing trunks.

Fig. 3 discloses a district selector switch of the coordinate type.

Fig. 4 illustrates a group selector switch of the coordinate type in which terminate

trunks incoming from the district selectors. 55

Fig. 5 shows one of a number of coordinate connector switches for completing connections to called lines and P. B. X. trunks.

Fig. 6 represents a sender selector switch 60 also of the coordinate type.

Figs. 7 and 8 illustrate one of a number of common register senders.

Fig. 9 shows at the left of the sheet a sender connector device for connecting any of the senders with the common marker or 65 selection controlling device.

The remainder of Fig. 9 together with Fig. 10 disclose the common marker for controlling the district switches.

Fig. 11 shows a sender connector device 70 for connecting the line marker with any of the several register senders. This figure also shows testing relays for testing the trunks interconnecting the group selector and connector switches together with certain 75 control elements of the line marker.

Fig. 12 discloses the remainder of the line marker.

Fig. 13 illustrates a second coordinate group selector switch similar to the switch 80 shown in Fig. 5 and belonging to the same group for establishing connections to called lines and P. B. X. trunks.

General description of system and apparatus. 85

The line switch 100, selector switches 300 and 400, connector switches 500 and 1300 and the sender selector switch 600 employed 90 in this system are of the coordinate type such as shown and described in the patent to S. B. Williams, No. 1,517,331, issued December 2, 1924. The subscribers' lines enter the exchange and appear in the coordinate line switches 100 in vertical rows 110 and 111, each line having access to a group of horizontal links such as the groups represented by links 106 and 107 and links 108 and 109. Line 101, for instance, has access 95 to the group of links containing the links 106 and 107. Each of the outgoing trunks 114, 115, etc., occupies a full vertical row of contacts 112, 113 and leads to the district switches. 100

Trunk 114 which is shown in full, appears in the district switch 300 in the vertical row of contacts 308. Another trunk 105

- 115 is shown occupying the vertical row of contacts 309. The district selector switch 300 also has a plurality of groups of outgoing trunks appearing in rows 311, 312, 313, etc. Each outgoing trunk is shown as having an appearance before a single horizontal link such as the links 303, 304, 305, 306 and 307. These trunks are multiplied to appear before corresponding horizontal links in a 10 number of district switches belonging to the same group. These other district switches also receive trunks incoming from other line switches similar to the switch 100 serving other calling lines in the exchange.
- 15 The subscribers' lines are divided into a number of groups as called lines known as terminal line groups. For convenience, there may be five of these terminal line groups accommodating an exchange of 10,000 lines in capacity, each such group serving 2,000 lines. As will be explained hereinafter, each terminal line group is made up of a number of group selectors and a number of connector switches. The trunks 20 outgoing from the district switches are, therefore, arranged to have access to any of the five terminal line groups of switching apparatus.
- 25 The group of trunks appearing in the upper section 302 of the vertical row 311 in the district switch 300 lead to the group selector switches of a particular terminal line group. One of these trunks 350 is shown extending to the group selector switch 400. The group of trunks occupying the lower section 301 of the same vertical row may lead to the group selectors of the same or of a different terminal line group as desired. Other groups outgoing from the district 30 switches are distributed to other terminal line groups. In addition to these groups of trunks, the district switches may have access to trunks extending in other directions.
- 35 As above observed each terminal line group of switching apparatus is equipped with a plurality of group selectors and a plurality of connector switches. There will be as many connector switches as are necessary to accommodate the 2,000 called subscribers' lines together with provision for as many P. B. X. trunks as may be required. There will be as many group selector switches as is necessary to extend the trunks incoming from the district switches 40 to the connectors. If there are 2,000 lines in the group having directory numbers together with a number of groups of P. B. X. trunks, these may be distributed in any suitable manner among as many connector switches as the total number of lines and trunks utilize.
- 45 Each of the several district subscribers' lines is provided with a directory number and occupies a given position in one of the connector switches. Moreover, for each 45 group of private branch exchange trunks there is a single call-line which has a directory number identifying the P. B. X. and which is located in the connector switches along with the regular subscribers' lines. The several trunks belonging to each private branch exchange group represented by a call-number line are, however, independent of directory numbers. In other words, for each P. B. X. call-line there may be as many trunks outgoing to the district P. B. X. represented as necessary and these may be located in one or in a number of connector switches in any arbitrary manner. In order to call a group of P. B. X. trunks, the subscriber dials a number identifying that particular P. B. X. group. The apparatus in the exchange establishes a connection through the district switch into the group selector of the proper terminal line group and thence from the group selector to the particular connector switch in which appears the corresponding call-line. Immediately that the call-line is selected the connection through the group selector and connector switches is released and is automatically reestablished through the group selector and the proper connector to the first idle P. B. X. trunk of the required group. If this first idle trunk is located in the same connector switch with the call-line, then the connection is reestablished to the connector switch first used. However, the first idle trunk may appear in a different connector switch, in which case, the reestablished connection leads to such other connector switch and thence to the selected idle P. B. X. trunk.
- 50 Considering the terminal line switching apparatus shown in the drawing there are illustrated a number of direct subscribers' lines 534, 535, and 1322 appearing in the connector switches 500 and 1300. There is also illustrated a P. B. X. call-line 538 appearing in the switch 500 and a number of P. B. X. trunks 536, 537, 539, 1323 and 1324 comprising the group represented by the call-line 538. It will be noted that a portion of these P. B. X. trunks are located in the switch 500 with the call-line 538, while the remainder of the trunks of this group are situated in a second and different connector switch 1300. It will be understood, as previously explained, that all of these trunks may be located on a single connector switch or that they may be distributed among still other connector switches in the group (not shown).
- 55 All numbered lines including both direct subscribers' lines and P. B. X. call-lines appear in the connector switches in groups or vertical rows according to their numbers. For instance, the vertical row of contacts 532 in the connector switch 500 represents a group of ten lines. Only three of

these lines are illustrated in the drawing, the two subscribers' lines 534 and 535 and the P. B. X. call-line 538. In the second switch 1300 shown, the vertical row 1320 represents another group of ten numbered lines. In like manner, there will be as many of these vertical ten-line groups in these and other connector switches as is necessary to accommodate the full 2,000 numbered lines. In addition to the numbered lines the P. B. X. groups also appear in vertical rows. The particular group shown occupies either all or a portion of the vertical row 533 in the switch 500 and also either all or a portion of the vertical row 1321 in the switch 1300 according to the number of trunks necessary for this particular group.

The connector switches are also provided with a number of groups of horizontal links, each group having access to all numbered lines of a particular units designation together with P. B. X. trunks. For example, the group of links comprising the links 501 and 502 have access to the call-line 538 in the row 532, to the trunk 536 in the row 533 and also to other lines or trunks in other rows (not shown). The horizontal test link 503 is associated with this group of horizontal links and serves for test purposes as hereinafter described. For each of the remaining nine units designations, there is a group of these horizontal links having access to lines and trunks. Two of these groups, one including the horizontal links 504, 505 and 506 and the other including links 507, 508 and 509, are illustrated. In a similar manner the switch 1300 has a number of groups of horizontal links of which the links 1301 to 1306 are a portion.

The district marker shown in Figs. 9 and 10 includes two sets of testing relays 1000 and 1003. The set 1000 serves to test the horizontal links of the section 302 in any district selector switch with which it is associated and also to test the outgoing trunks which have access to these links. The connecting device 1002 which comprises a number of multi-contact relays 1015, 1016, etc., serves to connect the set of relays 1000 with the proper group of outgoing trunks, the multi-contact relays each being individual to a different group. Likewise, the other set of test relays 1003 serves to test the set of horizontal links 301 in all switches and the outgoing trunks to which these links have access. Also a connecting device 1001 consisting of multi-contact relays 1022, 1023, 1019, 1020, 1025 and 1026 serves to connect the marker testing relays with the individual switches. Relays 1023, 1020 and 1026, for instance, are individual to the particular switch 300 shown in the drawing.

The line marker shown in Figs. 11 and 12 includes a plurality of registers 1200, 1201 and 1202 which receive numerical records

from the controlling sender. It also includes the multi-contact relay translating device 1204 which is operated according to the settings of the registers to select the vertical operating magnets 515, 1308, etc., 70 individual to the different vertical rows of numerical lines in the connector switches. Moreover, the line marker includes a multi-contact relay translating device 1203 which serves to associate the register 1201 with the connecting devices 510 and 1316 individual to the connector switches 500 and 1300, respectively. The device 510 consisting of relays 511, 512, 513, etc., serves to associate certain test relays in the marker with the horizontal links of the group having access to the called lines of the desired units designation in the connector switch 500. The device 1316 similarly comprising a number of multi-contact relays 1317, 1318, 85 etc., serves to connect the same testing relays in the marker with the horizontal links of the group having access to the called lines of the desired units designation in the connector switch 1300. In Fig. 11 the set of 90 testing relays of the marker are associable through the multi-contact relay connecting devices 401 and 402 with the groups of trunks outgoing from the selector switch 400 and other switches and with the horizontal links of these group selectors.

Detailed description of establishment of a connection.

It will first be considered that the subscriber of line 101 wishes to obtain connection with the private branch exchange represented by the call-line 538 appearing in the switch 500. For this purpose it will be assumed that the directory number of the P. B. X. in question is 1234. When the calling subscriber removes his receiver from the switchhook a circuit is closed from battery through the winding of line relay 121, inner contact of cut-off relay 120, conductor 104, through the substation loop, conductor 103 to ground through the outer contact of relay 120. Relay 121 operates and a circuit is closed from battery through the winding of relay 129, right back contact of relay 128, left contact of relay 121, conductor 110 105 and 156 to ground.

Relays 128, 129 and 130 enclosed within the broken rectangle pertain to the vertical group of lines in the row 110 of the switch 100. These relays are brought into action whenever one of the lines of the corresponding group initiates a call.

Relay 129 completes a circuit from battery 125 through the winding of relay 131, inner front contact of relay 129 to the grounded conductor 156. Relay 129 also closes a circuit from battery through the left hand winding of relay 130, outer front contact of relay 129, left back contact of relay 135, outer 130

right contact of relay 137, conductors 158 and 156 to ground. Relay 130 operates and closes a circuit for relay 128. Relay 128 locks through its left contact and the contacts of relays 131 and 132 to ground. Relay 130, in operating, completes a circuit from battery through its right hand winding and inner right contact, winding of relay 135, outer right contact of relay 137, conductor 158 to ground. Relay 135 operates and closes a circuit from battery through the winding of slow-to-release relay 136, inner right contact of relay 135, inner right back contact of relay 137, conductor 158 to ground. Relay 136 closes a substitute holding circuit for relays 130 and 135.

With relay 135 operated, a circuit is closed from battery through the winding of the vertical operating magnet 116, outer right front contact of relay 130, left front contact of relay 135, contact of relay 136, conductor 158 to ground. The magnet 116 operates and prepares the contacts in the vertical row 110. Magnet 116 also closes a circuit from ground through its contact, conductor 159, inner contact of relay 134, outer left contact of relay 130, right contact of relay 121, left hand winding of the horizontal group relay 122 to battery. Relay 122 is a group relay individual to the group of horizontal links including the links 106 and 107. Similarly, relay 123 is a group relay individual to the other group of horizontal links illustrated.

Relay 122 operates and closes a circuit from battery through its right hand winding and right contact, right back contact of relay 123, winding of relay 134, conductor 159 to ground. Relay 134 operates in this circuit. Another circuit is closed from battery through the winding of the vertical operating magnet 118, brush 144 of allotter switch 143, contact of slow release relay 139, left contact of relay 137, outer right contact of relay 135, conductor 158 to ground. It is assumed that the first one of the outgoing trunks 114 is idle and that the allotter switch 143 is standing in a position to allot this trunk as shown in the drawing. The allotter switch 143 has a position for each of the several trunks which lead out of the line switch 100 to the succeeding district selectors. Consequently, the vertical magnet 118 relative to the idle trunk 114 operates and prepares the contacts in the vertical row 112. Magnet 118, in operating, completes a circuit from battery through its winding and inner contact, conductor 160, winding of relay 137, outer right contact of relay 135, conductor 158 to ground. Relay 137, however, being shunted by the circuit above traced does not operate this time. Magnet 118, furthermore, closes a circuit from ground through its outer contact, conductor 151, winding of trunk relay 146 to battery. With relay 146 operated a circuit is completed from battery through the winding of relay 139, winding and contact of stepping magnet 138, brush 145, contact of relay 146 to ground over conductor 151. The magnet 138 operates, interrupts its own circuit and advances the brushes 144 and 145 to the next set of terminals. If the following trunk is idle then the allotter switch comes to rest, but if it is busy, the switch continues until an idle trunk is found. When the switch leaves the position shown it opens the shunt around relay 137 and this relay operates in series with magnet 118. Relay 137 opens the circuit of relay 136 which commences to deenergize. Relay 136 being slow, holds its armatures for an interval after the release of relay 137 which is sufficient for certain operations to take place.

During the interval mentioned a circuit is closed from ground over conductor 158, inner right front contact of relay 137, outer contact of relay 134, left back contact of relay 123, left front contact of relay 122, back contact of relay 127, assuming the first link 107 is idle, winding of magnet 125 to battery. Magnet 125 operates and effects a connection between the link 107 and the incoming line and also between the link and the outgoing trunk 114. Immediately that this connection is established, a circuit is closed from battery through the winding of magnet 125, winding of relay 127, contacts of the switch 100, over the sleeve conductor to ground at the outer contact of magnet 118. The switch is temporarily held by means of this circuit but relay 127 being shunted does not operate at this time. Another circuit is closed from battery through the winding of cut-off relay 120 over the sleeve conductor to ground at the contact of magnet 118. Relay 120 opens the circuit of relay 121, which in turn, opens the original energizing circuit of relay 129.

Should another line in the same vertical group attempt simultaneously to make a call while a subscriber in a succeeding vertical group is calling, his attempt to make such a call will be unsuccessful. When the line relay 121 releases following the opening of its circuit by relay 120, it opens the holding circuit of relay 131, but since the second subscriber in the same group is calling relay 131 is held energized over a parallel circuit through the left contact of the line relay similar to relay 121. Relay 131 in remaining energized preserves the locking circuit of relay 129 which prevents the reenergization of relay 129. A second subscriber in the first group who has removed his receiver while the line relay of the first calling subscriber is energized, therefore, cannot succeed in making a call until a simultaneous call in subsequent groups have been handled.

or until a call has been made in each of said succeeding groups. In this latter event a series circuit is closed for relay 132 through the back contacts of all relays similar to 5 relay 129 and relay 132 operates to unlock relay 128.

At the instant relay 146 energizes, the ground potential on conductor 151 is extended through the contact of this relay over 10 conductor 150, through the back contact of relay 204, conductor 206, thence through the winding of relay 613. Relay 613 operates and locks through its winding and inner left contact, conductor 207, outer left back contact of relay 201 to ground. Relay 613 completes a circuit from ground through its outer right contact, conductor 209, winding of slow-to-release relay 204 to battery. Relay 204 operates and applies holding ground 15 to the conductor 150, whereby magnet 125 and relays 120 and 146 are held energized when magnet 118 becomes deenergized. Relay 613 operates similarly to the relay 120 of the line switch and brings the group relays 25 614, 615 and 616 and the control relays 619, 620, 621, 617, 622 and 623 into play to cause the extension of a connection through the sender selector switch 600 to the allotted idle register sender.

With relays 616 and 617 operated a circuit is closed from battery through the winding of vertical magnet 629, contacts of relays 30 616 and 617, outer right contact of relay 623 to ground. Magnet 629 operates and brings about the energization of relay 612, which in turn, locks in a circuit including the relay 621. Relay 617 also closes a circuit from battery through the winding of vertical magnet 631, brush 627 of allotter 626, 35 contact of slow relay 625, left contact of relay 623, contact of relay 617 to ground. The magnet 631 operates and closes a locking circuit through its winding and contact and the winding of relay 623, the latter 40 relay, however, remaining deenergized due to the shunt around its winding. Magnet 631 also closes a circuit from ground through its outer contact, conductor 638, through the brush 628, contact and winding of magnet 50 624, winding of slow relay 625 to battery. Magnet 624 steps the switch 626 forward to the set of terminals representing the next idle sender and in so doing removes the shunt from the winding of relay 623. Relay 623 opens the circuit of slow-to-release 55 relay 622 which commences to deenergize. During the interval that relay 622 is deenergizing a circuit is closed from ground through the inner right front contact of relay 623, right contact of relay 621, left front contact of relay 612, front contact of relay 611, assuming the link 608 to be busy, back contact of relay 609, winding of the horizontal magnet 610 to battery. Magnet 610 60 operates the switch and connects the in-

coming trunk conductors through the link 607 to the group of conductors 632 leading to the selected idle sender.

Immediately that the connection is established a circuit is closed from battery 70 through the winding of relay 201, conductor 210, contacts of switch 600, conductor 638 to ground at the contact of magnet 631. Relay 201 operates and opens the circuit of relay 613 which causes the deenergization of 75 relays 612 and 619 provided no other sender is being sought through the same vertical group in the switch 600. Relay 201 also closes a holding circuit for the relay 204 which maintains a holding ground potential 80 on the conductor 150. Furthermore, relay 201 connects the tip and ring conductors of the trunk through the sender selector switch to the impulse relay 700 and balancing coil 701 of the sender. This results 85 in the closure of a circuit from battery through the resistance 718, winding of relay 700, outer left contact of relay 703, conductor 640, through contacts of the switch 600, conductor 641, outer right contact of 90 relay 201, conductor 149, thence through the line switch 100 and the subscriber's substation loop and returning over the other side of the line to conductor 148 to the inner right contact of relay 201, conductor 642, through the switch 600, conductor 643, inner left contact of relay 703, right hand winding of the balancing coil 701 to ground. Relay 700 operates and closes a circuit for 95 slow-to-release relay 702. Relay 702 places ground on the holding conductor 720. This ground potential is transmitted by way of conductor 638 and results in a holding circuit for the magnet 610 and relays 609 and 201 in substitution of the circuit temporarily 100 maintained by the vertical operating magnet 631.

Following the series of operations just related slow relays 136 and 622 become deenergized. Relay 136 opens the circuits of 110 relays 130 and 135. Relay 130 opens the circuit of magnet 116 and relay 135 opens the holding circuit of magnet 119 and relay 137. Magnet 116 causes the release of 115 relays 134 and 122. With the vertical magnets deenergized the connection is now held through the line switch 100 due to the maintained energization of magnet 125 which, as above mentioned, is held in a circuit closed 120 to ground over the sleeve conductor 150. Relay 127 now operates in series with magnet 125 and extends the horizontal start circuit to the next link. Relay 622, in releasing, similarly brings about a release of the 125 corresponding elements in the sender selector switch 600 and the connection through this switch is now held by the magnet 610, the circuit of which is controlled by the slow relay 702 in the sender. Relay 609 now 130 operates in series with magnet 610.

The apparatus is now in condition for receiving the first series of impulses. The calling subscriber, consequently, manipulates his impulse transmitter 163 to send a single impulse representing the first digit of the wanted number. At the time relay 702 operates it closes a circuit from battery through the winding of slow release relay 706, left back contact of relay 704, left back contact of relay 705, conductor 720, to ground at the left contact of relay 702. Relay 702 also closes a circuit from battery through the resistance 739, left hand winding of relay 707 to ground at the right contact of relay 702. Relay 707, however, does not operate since its winding is shunted by the following path: battery, through the resistance 739, contact of relay 700 to ground at the right contact of relay 702.

In response to the first opening of the line by the calling subscriber, relay 700 releases and opens the shunt around the winding of relay 707 and this latter relay operates. Relay 707 closes a circuit from battery through the winding of relay 704, outer left contact of relay 707 to the grounded conductor 720. Relay 704 operates and locks in a circuit through its left front contact, left contact of relay 705 to ground on conductor 720. Relay 704 opens the original circuit of relay 706, but this latter relay remains energized in a circuit traceable through the outer right front contact of relay 707 to the grounded conductor 720. Relay 707 closes a circuit through the left hand winding of relay 708 and relay 708 operates and closes a circuit from battery through its right hand winding and inner right contact to the grounded conductor 720.

Relay 708, in operating completes a circuit from battery through its left hand winding and left contact, conductor 724, outer right back contacts of counting relays 715, 714, 713 and 712 in series, winding of relay 712, outer left back contact of relay 713, conductors 725 and 726, outer right contact of relay 705, left front contact of relay 704, left contact of relay 705 to the grounded conductor 720. So long as relay 707 remains operated relay 712 is shunted and does not receive sufficient current in the circuit traced to energize. At the end of the impulse relay 700 operates and shunts relay 707 and this relay releases, opening the original circuit through the left hand winding of relay 708. Relay 712 now operates in series with the left hand winding of relay 708. Relay 712 locks in a circuit from battery over conductor 727, inner right contact and winding of relay 712, outer left back contact of relay 713 to ground over conductor 725.

It should be noted at this point that the armatures of the counting relay 712, which is also true of the remaining counting relays, are so arranged that the inner right contact

is closed slightly in advance of the opening of the outer right back contacts. By this arrangement the locking of the relay is certain to occur before the energizing circuit is opened.

70

Immediately that the relay 712 opens its back contact the circuit through the left hand winding of relay 708 is opened. Relay 708 is wound differentially and when the left hand winding is opened, the effect of the right hand winding is to cause a quick release.

75

After the usual interval has elapsed following this impulse, slow-to-release relay 706 becomes deenergized and a circuit is completed from ground over conductor 720, contact of relay 706, right contact of relay 704, inner right contact of relay 705, conductor 722, right back contact of relay 808, winding of relay 807 to battery. Relay 807 operates and closes a circuit from battery through its winding and inner upper contact, thence over conductor 830 winding of relay 705, through contacts of relays 704, and 706 to ground. Relay 705, however, being shunted by the above circuit does not operate at this time. Relay 807 serves to connect the counting relays to the register relays of the register 800. With relay 807 operated and relay 712 energized a circuit is closed from the grounded conductor 725, outer left front contact of relay 712, conductor 728, outer right back contact of relay 717, conductor 729, conductor 831, contact of relay 807, thence in parallel one branch leading through the winding of relay 804 and the winding of relay 832 to battery and the other branch leading through the winding of relay 823 to battery. Relays 804, 832 and 823 operate and lock through the inner left front contact of relay 804, conductor 825 to the grounded conductor 720. Relay 832 closes an obvious circuit for relay 808 which operates and locks to the grounded conductor 825. Relay 808 opens the shunt around the winding of relay 705, which energizes in series with relay 807. Relay 705 opens the circuit of relay 704, which in turn, opens the circuits of relays 705 and 807. Relay 807 disconnects the counting relay from the register 800. With relays 704 and 705 de-energized relay 706 again operates in the circuit above traced. Relay 705 also releases relay 712.

90

The subscriber operates his dial to transmit the second series consisting of two impulses and in the manner already fully explained relays 712 and 713 are operated. Relay 713, in operating, opens the holding circuit of relay 712 which thereupon releases. After the proper interval has elapsed following the series, slow relay 706 releases and a circuit is closed from ground over conductor 722 as above traced, through the right front contact of relay 808, right back contact of

120

125

130

- relay 812, winding of relay 811 to battery. Relay 811 operates, connects the counting relays to the second register 801 and closes a locking circuit through its winding and 5 inner upper contact, over conductor 830 as previously traced, through the winding of relay 705. Relay 705 being shunted does not operate at this time.

Since the counting relay 713 is operated a 10 circuit is traceable from the grounded conductor 725, through the outer left front contact of relay 713, conductor 730, conductor 837, through contact of relay 811 winding of register relay 810 to battery. Relay 810 locks through its inner left contact to the 15 grounded conductor 825. Relay 810 at its outer left contact closes a circuit for relay 812 which operates and locks to the conductor 825. Relay 812 opens the shunt 20 around relay 705 which operates and in the manner explained brings about the release of relay 704, relay 713 and relay 811 and also releases itself.

The subscriber next transmits the third 25 series consisting of three impulses. In response to this series relays 712, 713 and 714 are operated and relays 712 and 713 successively release. After an interval relay 706 releases and closes a circuit as traced 30 over conductor 722, through the right front contacts of relays 808 and 812, right back contact of relay 816, winding of relay 815 to battery. Relay 815 operates, connects the 35 counting relays to the register 802 and closes a locking circuit for itself over conductor 830 through the winding of relay 705.

With relay 815 operated and the counting relay 714 energized, circuits are closed from ground over conductor 725, through the left 40 front contacts of relay 714, conductors 729 and 730, thence over conductors 831 and 837, through contacts of relay 815, windings of relays 813 and 814 to battery. Relays 813 and 814 lock through their inner left contacts to the grounded conductors 825. These 45 relays also close a circuit for the relay 816 which operates and locks through its left contact to the conductor 825. Relay 816 opens the shunt around relay 705, which in turn, operates in series with relay 815. In 50 a similar manner to that already explained relay 705 brings about its own release and the release of relays 704 and 815.

The subscriber now transmits the final 55 series consisting of four impulses. In response to this series counting relays 712, 713, 714 and 715 are operated in succession and relays 712, 713 and 714 are released in succession. After an interval relay 706 releases and a circuit is closed by way of conductor 722, through the right front contacts of relays 808, 812 and 816, right contact of relay 820, winding of relay 819 to battery. Relay 819 connects the counting 60 relays to the register 803 and closes a lock-

ing circuit for itself over conductor 830, through the winding of relay 705. With relay 819 operated and relay 715 operated a circuit may be traced from ground over conductor 725, outer left back contact of relay 712, inner left contact of relay 715, conductor 731, conductor 838, through contact of relay 819, relay 833 to battery. Relay 833 locks through its inner left contact to the grounded conductor 825. Relay 833 closes a circuit for relay 820 which locks through its inner left contact to conductor 825. Relay 820 opens the shunt around relay 705 which brings about its own release and the release of relays 704 and 819. 89

As soon as the thousand digit is recorded on the register 800, the sender is connected to the district marker in order that the record may be transferred thereto for determining the group selective operation of 85 the district switch 300. When relay 808 operates a circuit is established from the grounded conductor 825, through the outer left contact of relay 808, conductor 839, winding of relay 709 to battery. Relay 709 90 operates and locks through its outer contact to the grounded conductor 720. Relay 709 closes a circuit from the grounded conductor 720, through the outer left contact of relay 711, inner contact of relay 709, conductor 732, winding of relay 904 to battery. Relay 904 closes a circuit from ground through its right contact, right contact of relay 907, winding of relay 908 to battery. Relay 908 operates and locks through its 95 inner contact, middle back contact of relay 909, conductor 914, contact of slow relay 912 to ground. Relay 908 closes a circuit from battery through the right winding of relay 903, left contact of relay 904, left 100 back contact of relay 906, outer contact of relay 908, middle back contact of relay 909, conductor 914 to ground. Relay 903 closes a circuit for relay 907. Relay 907, in turn, closes a circuit from battery through the 105 left winding and contact of relay 903, left back contact of relay 905, left contact of relay 907, winding of relay 909 to ground over conductor 914. Relay 903 is locked and relay 909 operates in this circuit. Relay 110 115 908 now becomes released. Relay 909 causes a circuit to be closed for the multi-contact relay 901, which is individual to the particular sender shown and serves to connect that sender with the district marker. Another multi-contact relay 902 is individual to another sender and serves for a similar purpose. The circuit of relay 901 leads from battery through the winding thereof, inner right contact of relay 903, inner contact of relay 909 to the grounded conductor 914. Relay 901, in operating, closes a circuit from ground through its contact, outermost contact of relay 909, inner left back 120 125 contact of relay 911, winding of relay 910 130

to battery. Relay 910 operates and closes a circuit from ground over conductor 914, through the middle front contact of relay 909, left contact of relay 910, conductor 915, outer left back contact of relay 1046, winding of slow-to-release relay 1048 to battery. Relay 1048 operates and closes a circuit for slow-to-release relay 1047.

Relay 910 also closes a circuit for the vertical operating magnet 315 of the district switch 300 which controls the row of contacts in which appears the trunk 114. This circuit may be traced from ground over conductor 914, through the middle front contact of relay 909, left contact of relay 910, conductor 915, contact of relay 901, conductor 919, inner left contact of relay 711, conductor 734, contacts of switch 600, conductor 645, outer right contact of relay 205, conductor 212, winding of magnet 315, to battery. Magnet 315 prepares the contacts in the row 308 and also closes a circuit through its right contact, conductor 327, winding of multi-contact relays 1023, 1020 and 1026 in parallel to battery. These relays are individual to the district switch 300 and serve to connect the common marker thereto. Magnet 315 also completes a circuit from battery through the winding of relay 208, conductor 213, left front contact of magnet 315, conductor 215, through the inner left contact of relay 201 to the grounded conductor 150. Relay 208 operates and locks through its outer right contact to conductor 215.

Relay 910 also closes a circuit from the grounded conductor 914, through the right contact of relay 910, conductor 916, contacts of relay 901, conductor 917, outer right back contact of relay 882, right back contacts of relays 836, 835 and 805 in series, thence through the inner right back contact of relay 822, conductor 840, contact of relay 901, winding of relay 920 to battery. Relay 920 represents the thousands digit 1 in the marker and is operated due to the fact that this digit is registered on the register 800 of the sender. By inspection of the circuits it will be found that the other relays 921, 922, 923, etc., in the marker are operated when other thousands digits are recorded on the register 800 in the sender. With relay 920 energized a circuit is closed from the grounded conductor 916, through the contact of relay 920, conductor 925, winding of relay 1034, to battery. Relay 1034 is individual to the group of trunks which occupies the section 302 of the vertical row 311 outgoing from the district switch 300 leading to the terminal line switching group having access to called lines whose thousands digit is 1.

When relay 1034 operates it closes a circuit from ground through its lowermost contact, winding of relay 1046, to battery. Re-

lay 1046 opens the circuit of relay 1048 which commences to release. During the release period of relay 1048, test relays 1000 are connected in the manner about to be described to the test conductors of the selected outgoing trunks to ascertain an idle trunk corresponding with an idle link. Relay 1046 closes a circuit from ground through its inner left contact, right front contact of relay 1047, upper front contact 75 of relay 1034, conductor 1042, contact of relay 1026, conductor 1043, winding of the vertical operating magnet 318 to battery. Magnet 318 prepares the contacts in the row 311 and also closes a circuit from ground 80 through its contact, conductor 334, contact of relay 1026, conductor 1044, winding of relay 1049 to battery.

The testing operation will now be described. To connect the test relays to the test conductors of the trunks the multi-contact relay 1015 individual to the group of trunks involved is operated over the following circuit: Battery, through the winding of said relay, through the middle lower contact of relay 1034, conductor 1045, contact of relay 1026, conductor 1050, left contact of relay 1047, outer left front contact of relay 1046, conductor 915 to ground. Relay 1015 connects the right hand windings 95 of the double wound test relays of the group 1000 to the respective test conductors of the outgoing trunks. The left hand windings of these relays are connected through the contacts of relay 1023 to the test conductors 100 of the corresponding horizontal links conductors. If, for example, the lowermost trunk in the section 302 of the vertical row 311 is busy, a circuit is closed from grounded sleeve conductor 335, through a contact 105 of relay 1015, right contact of relay 1037, right hand winding of test relay 1038 to battery. Relay 1038 operates and locks through its right hand winding, conductor 1059 to ground at the outer right contact of relay 110 1046. If the corresponding horizontal link 306 is busy, a circuit is also closed from the sleeve conductor of the link by way of conductor 337, contact of relay 1023, outer left back contact of relay 1037, left winding of 115 relay 1038 to battery. Either winding of any test relay is sufficient to operate the same. Provided the trunk 350 and its corresponding link 307 are both idle, the corresponding test relay 1041 remains deenergized. 120

After an interval the relay 1048 releases and a circuit is closed from ground over conductor 915, right contact of relay 1049, right contact of relay 1048, inner right contact of relay 1046, conductor 1052, thence through the contact of relay 1015, inner left front contact of relay 1038, inner left back contact of relay 1039, winding of relay 1040 to battery. It will be noted that relay 1036 125

is operated in a circuit closed through the left contact of relay 1038 to ground over conductor 1059. With relay 1040 operated a circuit is closed from ground through the 5 left contact of relay 1049, conductor 1053, through the contact of relay 1015, right front contact of relay 1036, right back contact of relay 1039, left front contacts of relay 1040, contacts of relay 1023, thence over 10 conductors 1054 and 1055, windings of horizontal magnet 326 to battery. The magnet 326 operates and effects a connection between the incoming trunk 114 and the idle outgoing trunk 350 by way of link 307. Immediately 15 that the connection is established the magnet 326 is locked in a circuit through its right hand winding, contact of switch 300 to the grounded test conductor 150. After an interval following the release of 20 relay 1048 relay 1047 becomes deenergized and in so doing opens the circuit of relay 1015 whereby the test relays are disconnected from the outgoing group of trunks. Relay 1047 also opens the circuit of the 25 vertical magnet 318. Magnet 318 causes the release of relay 1049. With relay 1047 deenergized a circuit is closed from ground through the inner left contact of relay 1046, right back contact of relay 1047, conductor 1057, winding of relay 911 to battery. Relay 911 causes the release of the district 30 marker which is no longer required in connection with the present call.

Relay 911, in operating, closes a circuit 35 for relay 912 but this relay being both slow to operate and slow to release, requires an interval of time before it attracts its armature. During this interval a circuit is closed from ground over conductor 914, 40 through the outer left contact of relay 911, conductor 927, contacts of relay 901, conductor 928, winding of relay 711 to battery. Relay 711 operates and locks to the grounded conductor 720. Relay 911 also opens the 45 circuit of relay 910 which releases and opens conductors 915 and 916. After a further interval relay 912 operates and removing ground from conductor 914 causes the release of the operated relays in Fig. 9 and the 50 disconnection of the district marker from the sender by the release of multi-contact relay 901. The vertical magnets 315 and 318 having been deenergized the connection through the district switch is held by the 55 maintained operation of the horizontal magnet 326.

When the magnet 315 releases a circuit is closed from battery through the winding of relay 205, inner right contact of relay 208, conductor 214, left back contact of magnet 315, conductor 215, through the contact of relay 201 to the grounded conductor 150. Relay 205 operates and locks through its inner right contact. 60

With relay 711 operated a circuit is closed 65 from ground through the outer left contact of relay 820, conductor 841, outer right contact of relay 750, inner left contact of relay 710, inner right contact of relay 711, conductor 842, thence in parallel, through the 70 winding of relays 843, 821 and 822 to battery. Since the thousands digit is 1 and since only the register relay 804 of the register 75 800 is operated, a circuit is now completed through the front contact of one of the switching relays 821 and 822 for operating the relay 1112 to cause the connection of the register sender to the line marker which controls the final group switching equipment having access to the No. 1000 80 lines. This circuit leads from ground over conductor 842, as previously traced, through the outer right front contact of relay 822, right back contacts of relays 836, 835 and 805, inner right front contact of relay 822, 85 conductor 930, winding of relay 1112 to battery. Relay 1112 operates and closes a circuit for relay 1116. Relay 1116 locks through its right contact, outer right back contact of relay 1114, conductor 1140 to ground through the contact of slow relay 1117. Relay 1116 closes a circuit from battery through the right hand winding of relay 1110, left contacts of relays 1112 and 1113, left contact of relay 1116, outer right back 90 contact of relay 1114 to the grounded conductor 1140. Relay 1110 closes an obvious circuit for relay 1115. Relay 1115 closes a circuit from battery through the left hand winding and contact of relay 1110, left back 95 contact of relay 1111, left contact of relay 1115, winding of relay 1114 to grounded conductor 1140. Relay 1110 locks and relay 1114 operates in this circuit. A circuit is now established from battery through the 100 multi-contact relay 1108, outer right contact of relay 1110, inner left contact of relay 1114 to grounded conductor 1140. Relay 1108 operates and connects the sender to the line marker. Relay 1108 also closes a 105 circuit through its contact, outer left contact of relay 1114, outer left back contact of relay 1119, winding of relay 1118 to battery. 110

One of the first things to take place upon the connection of the line marker to the sender is the closure of a circuit for the vertical operating magnet 406 of the group selector 400 in which terminates the selected 115 trunk 350 outgoing from the district switch 300. This circuit may be traced from the grounded conductor 1140, inner right contact of relay 1114, contact of relay 1118, conductor 1141, contact of relay 1108, conductor 1142, contact of relay 843, conductor 844, outer right contact of relay 710, conductor 740, contacts of switch 600, conductor 646, outer left contact of relay 205, outer left front contact of relay 208, over the tip 120 of the trunk 114, through the switch 300, 125 130

over the tip of trunk 350, contact of relay 418, winding of magnet 406 to battery. Magnet 406 prepares the contacts in the vertical row of the switch 400 and closes a 5 circuit for multi-contact relay 412. Relay 412 connects the test relays of the line marker with the horizontal links of the switch 400 for testing purposes.

The record of the thousands, hundreds 10 and units digit is now transferred from the registers of the sender to the line marker. The relays 1218 and 1219 serve to determine whether the thousands digit is even or odd according to the combination in which they 15 are operated. In the present case the digit being 1 and odd, the relay 823 alone in the sender is operated. Relay 823 closes a circuit from ground over conductor 1142 as above traced, contact of relay 823, conductor 20 845, contacts of relay 1108, conductor 1143, winding of relay 1218 to battery. A circuit is now closed from battery through the winding of multi-contact relay 1228, right front contact of relay 1218, right back contact 25 of relay 1219 to the grounded conductors 1243 and 1141.

Another circuit may be traced from ground over conductor 1142, through the right contact of relay 810, conductor 846, 30 contacts of relay 1108, conductor 1144, winding of relay 1215 to battery. Other circuits are traceable over conductor 1142, through the right contacts of relays 813 and 814, conductors 847 and 848, contacts of relay 1108, conductors 1145 and 1146, windings of relays 1206 and 1207 to battery. Still another circuit leads from ground over conductor 1142, through the right contact of 35 relay 833, conductor 849, contacts of relay 1108, conductor 1147, winding of relay 1212 to battery.

With relay 1215 operated a circuit is closed from ground over conductor 1141, conductor 1158, inner left contact of relay 1159, 40 conductor 1160, conductor 1232, inner right back contacts of relays 1217 and 1216, inner right front contact of relay 1215, inner left back contact of relay 1214, winding of multi-contact relay 1226 to battery. Since both 45 relays 1228 and 1226 are operated a circuit is closed from battery through the winding of relay 1230, contacts of relays 1228 and 1226 in series, conductor 1233, inner left back contact of relay 1161, outer right back contact of relay 1159 to ground over conductors 1158 and 1141.

The translator device 1204 is made up of two sections of horizontal conductors, one of which is controlled by the odd thousands 50 relay 1228 and the other by the even thousands relay 1227. There being two thousand lines in this terminal line group, the relay 1228 serves to connect the conductors from the tens register 1202 to the 55 upper section of horizontal conductors in

the translator 1204 and the relay 1227 serves to connect the conductors from the tens register to the lower sections of horizontal conductors in the translator. The several multi-contact relays 1226, etc., extending to the 60 right are controlled by the hundreds register 1200. By means of the joint settings of the three registers and the translator device 1204 any group of ten lines may be selected on any one of the several connector switches 65 in the terminal line group.

In the present case where the tens digit is 3 and the two relays 1206 and 1207 of the register 1202 are operated, a selecting circuit is completed as follows for selecting a group 70 of ten lines occurring in the vertical row 532 on the connector switch 500 which contains the desired P. B. X. call-line 538: ground, over conductors 1141 and 1158, through the outer right back contact of relay 1159, inner left back contact of relay 1161, conductor 1233, contact of relay 1230, inner right back contacts of relays 1209 and 1208, inner right front contact of relay 1207, inner 75 left front contact of relay 1206, conductor 1239, contact of relay 1228, contact of relay 1226, conductor 1240, winding of the vertical operating magnet 515 to battery. The magnet 515 operates the associated rod and prepares the contacts of all lines in the vertical 80 row 532. The magnet 515 in addition completes a circuit from ground through its contact, conductor 540 and thence in parallel, through the windings of multi-contact relays 1220 and 416 to battery. The relay 1220 is 85 individual to the connector switch 500 and serves to connect the units register 1201 to the multi-contact relay device 510. The relay 416 is individual to the particular group 90 of trunks outgoing from the group selector switch 400 which leads to the connector switch 500 and it serves to connect the testing relays of the marker with the sleeve conductors of these trunks. Immediately that the relay 416 operates it closes the circuit 95 for the vertical operating magnet 408 which controls the contacts of the group of trunks outgoing from the group selector switch 400 to the connector switch 500. The magnet 408 prepares these contacts for operation.

Magnet 408, in operating, closes a circuit from ground through its contact and a contact of relay 412, conductor 423, winding of slow-to-release relay 1121 to battery. It will be noted that the multi-contact relay 412, which is individual to the particular group selector switch 400 is operated by means of a circuit closed at the contact of the vertical operating magnet 406. The multi-contact relay 412 serves to connect the horizontal magnets and links of the selector switch 400 to the line marker. Relay 1121 now operating closes a 110 circuit from the grounded conductor 1141, 115 120 125 130

- thence over conductor 1158, outer right back contact of relay 1159, outer contact of relay 1121, conductor 1162, left back contact of relay 1137, outer left contact of relay 1161, 5 winding of slow-to-release relay 1138 to battery. Relay 1138 closes a circuit from ground over conductor 1158, through its inner left contact, conductor 1163, winding of slow-to-release relay 1123 to battery.
- 10 Relay 1123 operates and closes a circuit from battery through the winding of slow-to-release relay 1124, right front contact of relay 1123 to the grounded conductor 1141. Relay 1124 closes a circuit from battery through the winding of relay 1125, front contact of relay 1124, conductor 1164, outer right front contact of relay 1114, to the grounded conductor 1140. Relay 1125 operates and locks to the grounded conductor 1164. 15
- 20 With the apparatus in its present stage of operation, a test is made of the group of trunks extending between the group selector 400 and the particular connector switch 500 to ascertain a particular one thereof that is idle coincidental with the idle condition of the associated horizontal link in the switch 400. If the first trunk 420 in the selected group is busy a circuit is closed from battery through the right hand winding of test relay 1134, inner right contact of relay 1136, conductor 1165, contacts of relay 416 to the grounded test conductor 427 of the busy trunk 420. If the link 403 associated with 25 the trunk 430 is also busy a circuit is closed from battery through the left winding of relay 1134, outer left back contact of relay 1136, conductor 1166, contacts of relay 412 to the grounded sleeve conductor of the link 403. Either winding of the relay 1134 is sufficient to operate the same, and this is true of the succeeding test relays in the group. Relay 1134, in operating, locks through its right winding and right contact, conductor 1149, outer right back contact of relay 1159 to the grounded conductor 1158. Relay 1134 closes the circuit for relay 1135 extending through the left contact of said relay 1134 to ground over conductor 1149 as traced. 30
- 35 If the next trunk 421 in the group or its associated link is busy, or if both are busy, corresponding test relay 1131 is operated in a similar manner and causes the operation of relay 1132. Assuming, however, that the next trunk 422 is idle and that the corresponding link 405 is also idle, the corresponding test relay 1128 remains deenergized. 40
- 45 A circuit may now be traced from the grounded conductor 1141, conductor 1158, outer right back contact of relay 1159, inner contact of relay 1121, conductor 1167, inner left front contacts of relays 1135 and 1132, inner left back contact of relay 1129, winding of relay 1130 to battery. With relay 1130
- operated a circuit is closed for the vertical operating magnet 514 in the connector switch 500 which controls the row of contacts 530 in which appears the selected idle trunk 422. This circuit may be traced from ground over conductors 1141 and 1158, thence through the outer right back contact of relay 1159, outer contact of relay 1121, conductor 1162, outer right contact of relay 1130, middle right contact of relay 1129, conductor 1168, contact of relay 416, conductor 424, winding of magnet 514 to battery. The magnet 514 prepares the contacts in the associated row and also closes a circuit from ground through its contact, conductor 518, contact of relay 416, winding of relay 1137, to battery. Relay 1137, in operating, opens the circuit of relay 1138, but this latter relay being slow to release, requires an appreciable interval of time to 45 retract its armatures.
- 50 While the foregoing operations are taking place, a test is made to determine that the call is for a P. B. X. group of trunks. At the time relay 1220 operates, it closes a circuit from battery through the winding of relay 1235, contact of relay 1220, conductor 1160, and thence to ground as previously traced. Relay 1235 operates and completes a circuit from ground over conductor 1160, contact of relay 1235, inner right contact of relay 1213, inner right front contact of relay 1212, conductor 1236, contact of relay 1220, thence through the winding of multi-contact relay 511 to battery. Relay 511 operates and a circuit is closed as follows for the horizontal test magnet 520 controlling the test link common to the group of horizontal test trunks having access to the P. B. X. call-line 538: battery, through the winding of magnet 520, contacts of relay 511, conductor 541, left front contact of relay 1137, conductor 1162, and thence to ground over the path previously traced. The magnet 520 effects a connection between the horizontal test link 503 and the contacts in the vertical rows 530 and 532. This results in the closure of a circuit from battery, through the winding of relay 548 connecting block 544, contacts in the row 532, conductor 545 of the test link 503, contacts in the row 530, conductor 547, to the grounded conductor 1141. The relay 543 is individual to the called group of trunks and operates as above described when the connector switch 500 is operated to seize the call-line 538. Relay 543 locks through its inner left contact to the grounded conductor 1141. During the time that the connector switch is being operated and relay 543 is being energized, slow relay 1138 is maintaining its armatures attracted. Hence when the relay 543 operates a circuit is closed from the grounded conductor 1141, through the outer left contact of relay 543, conductor 548, right contact of 55
- 60
- 65

relay 1138, winding of relay 1159 to battery. Relay 1159 operates and locks through its inner right front contact to the grounded conductor 1158.

5 It will be noted that the relay 1169 was operated in a circuit from battery through its winding, inner right back contact of relay 1159, conductor 1158, conductor 1141, through the contact of relay 1118 to ground 10 as previously explained at the time said relay 1118 was first energized.

When as above described relay 1159 operates it opens the circuit of relay 1169, which being slow-to-release, requires a definite interval of time to retract its armatures. Relay 1159, in operating, removes ground from conductors 1160, 1149 and 1242. The removal of ground from these conductors results in the release of relay 1230, vertical operating magnet 515, relay 1226, relay 1235, relay 511 and magnet 514 and all energized testing relays in the marker. Magnet 515 removes ground from conductor 540 causing the release of relays 1220 and 416. Relay 511 opens the circuit of the horizontal test magnet 520. With magnet 514 deenergized the operating circuit of relay 1137 is opened. Relay 416, in releasing opens the circuit of the vertical operating magnet 408. Thus, 25 the seizure of the P. B. X. call-line and the operation of relay 1159 causes the release of the connector switch and the release of the group of trunks outgoing from the group selector 400 to such connector switch and 30 also the disassociation of the line marker from the connector switch. However, the vertical operating magnet 406 of the group selector remains operated and the testing relays in the marker remain associated with 35 the group selector switch through the multi-contact relay 412.

After an interval following the operation of relay 1159, the relay 1169 becomes deenergized and a circuit is closed from battery 45 through the winding of relay 1161, right contact of relay 1169, inner right contact of relay 1159 to the grounded conductor 1158. Relay 1161 operates and closes a circuit for the vertical operating magnet on the particular connector switch in which appears the 50 first idle P. B. X. trunk in the group. In the present case it will be assumed that the first two trunks in order, trunks 536 and 537 in the group are busy, while the third trunk 539 is the first idle one. Since the trunks 536 and 537 are both busy, the corresponding individual relays 550 and 551 are energized. Relay 552 individual to the idle 55 trunk 539, however, is deenergized. Accordingly, the selected circuit above mentioned 60 results in the energization of the vertical operating magnet 516 controlling the row of contacts 533 in the switch 500. This circuit may be traced from ground over conductors 1141, 1243 and 1244, outer right contact of

relay 1161, conductor 1170, outer right contact of relay 543, left front contacts of relays 550 and 551, left back contact of relay 552, winding of magnet 516 to battery. Magnet 516 operates and prepares the contacts in the 70 row 533 and closes a circuit by way of conductor 540 as previously traced for relays 1220 and 416. Relay 416 again closes the circuit of the vertical magnet 408, which in turn, recloses the circuit of relay 1121. 75

Another test is made of the group of trunks leading between the group selector 400 and the connector 500 and, provided the trunk 422 is the first idle one, the previously traced circuit is completed for the 80 vertical operating magnet 514. Magnet 514 causes the reoperation of relay 1137.

Relay 1161 closes another circuit from ground over conductor 1244, through the inner right front contact of said relay, conductor 1245, winding of the multi-contact relay 1246, to battery. Relay 1246 relates to the group of P. B. X. trunks and serves in conjunction with relay 1220 to operate the device 510 in accordance with the units 85 location of the selected idle trunk on the switch 500. With both relays 1220 and 1246 operated a circuit may be traced from ground over conductor 1158, through the outer right front contact of relay 1159, left 90 contact of relay 1169, conductor 1171, inner right contact of relay 543, right front contact of relays 550 and 551, right back contact of relay 552, conductor 553, contacts of relays 1246 and 1220, thence through the 95 winding of multi-contact relay 513 to battery. Relay 513 associates the test relays 1222, 1224, etc., with respective horizontal links 507, 508, etc., in the group having access to the idle P. B. X. trunk. If the first 100 link 507 is busy, a circuit is closed from battery, through the right winding of relay 1222, left contact of relay 1221, contacts of relay 513 to the grounded sleeve conductor of the link 507. Relay 1222 operates and locks through its left winding and contact, conductor 1242, inner left front contact of relay 1161 to ground over conductor 1244. If the next link 508 is idle, corresponding 105 relay 1224 remains deenergized. 110

At the time relay 1159 first operates a circuit is closed from battery through the winding of relay 1123, conductor 1163, outer left contact of relay 1159, inner right back contact of relay 1161 to the grounded conductor 1244. Relay 1123 operates and in the manner above described causes the operation of relay 1124. Relay 1125 is still locked to the grounded conductor 1164. When the relay 1161 subsequently operates it opens the circuit of relay 1123 which commences to release. After an interval has elapsed relay 1123 becomes deenergized and opens the circuit of relay 1124. Relay 1123 also closes a circuit from the grounded conductor 1141, 115 120

125

130

through the right back contact of relay 1123, right contact of relay 1122, outer left contact of relay 1125, conductor 1172, inner right front contacts of relays 1135 and 1132, inner 5 right back contact of relay 1129, left front contacts of relay 1130, thence through the contacts of relay 412 and the windings of the horizontal magnet 411 to battery. Magnet 411 operates and establishes a connection 10 between the incoming trunk 350 and the outgoing trunk 422, through the link 405. Immediately that the magnet 411 operates a circuit is closed from battery through the winding of relay 417, 15 through contacts of the switch 400, and thence to ground as traced over the above described circuit. Relay 417 operates and immediately locks through its left contact to the grounded sleeve conductor of the trunk 20 350. Moreover, magnet 411 locks through its right hand winding, contacts of the switch 400, through the left contact of relay 417 to the grounded sleeve conductor. Relay 417 closes a circuit for relay 418, which 25 in turn, opens the circuit for magnet 406. Still another circuit is traceable from the grounded conductor 1141, through the right back contacts of relays 1123 and 1122, inner left contact of relay 1125, conductor 1151, 30 right front contact of relay 1222, right back contact of relay 1224, winding of relay 1223, to battery. Relay 1223 operates and the grounded conductor 1151 is extended through the right contact of relay 1223, thence over 35 conductor 1237, through contacts of relay 513, left winding of horizontal magnet 525 to battery. Magnet 525 operates and effects a connection between the incoming trunk 422 and the idle P. B. X. trunk 539 through the 40 medium of link 508. The magnet 525 locks in a circuit through its right winding, contacts of the switch 500, thence over the sleeve conductor of trunk 422, through contacts of the switch 400 to the grounded sleeve conductor of the incoming trunk 350.

After an interval following the release of relay 1123 the slow relay 1124 becomes deenergized and closes a circuit from ground over conductor 1164, back contact of relay 50 1124, outer right contact of relay 1125, winding of release relay 1119 to battery. Relay 1119 operates and closes a circuit for relay 1117. Relay 1117, however, is slow to operate and requires an interval before it attracts its armature. During this time a circuit is established from ground through the contact of relay 1117, right contact of relay 1119, conductor 1153, contacts of relay 1108, conductor 1154, winding of relay 710 to battery. Relay 710 operates and locks to the grounded conductor 720. Relay 1119, in operating, opens the circuit of relay 1118 which removes ground from the conductor 1141 bringing about the release of the several 55 relays in the line marker which have been

held in circuits depending upon this grounded conductor. After an interval relay 1117 operates and removes ground from conductor 1140 causing the release of the remaining operated relays and magnets. Relay 1108 70 is also released to disconnect the register sender from the line marker. With the vertical magnets 406, 408, 514 and 516 all released, as a result of the disassociation of the line marker from the group selector and connector switches 400 and 500, the connection is held through to the selected P. B. X. trunk by the maintained operation of the horizontal magnets 411 and 525. Thus, the connection has been extended through to the P. B. X. trunk 539 and the individual relay 552 now operates over the sleeve conductor to identify this trunk as busy in case a subsequent connection is attempted in this same group. 80

Relay 710, in operating, brings about the operation of relay 703 which causes the release of the sender. The circuit for relay 703 extends from battery through the winding thereof, outer left contact of relay 710, outer right contact of relay 750, conductor 841, to ground at the outer left contact of relay 820. Relay 703 opens the holding circuit of relay 700 which releases and opens the circuit of relay 702. After an interval relay 702 releases and removes ground from the holding conductor 720, whereby all energized relays of the registers and all other relays locked to the conductor 720 are released. With the removal of ground from conductor 720 and 638 the horizontal magnet 610 of the sender selector is deenergized thereby disconnecting the sender from the trunk. 90

The removal of ground from conductor 638 and the release of switch 600 also opens the holding circuit of relay 201. Relay 201 extends the tip and ring conductors of the trunk 114 through to the repeating coil 227. The extension of the calling line to the repeating coil closes a circuit for relay 203 which operates and provides a substitute circuit for relay 204 since the circuit which previously held relay 204 is now open at the outer left contact of relay 201. Relay 201 at its inner left contact also opens the holding circuits of relays 208 and 205. Relay 208 completes the tip and ring conductors of the trunk 114 through to the right hand windings of repeating coil 227. 100

Release of the established connection.

After the conversation is finished and the calling subscriber replaces his receiver on the switchhook, relay 203 becomes deenergized. After an interval the slow relay 204 releases and removes ground from the sleeve conductor 150. This causes the deenergization of the operating magnet 125 of the line switch 100, relay 120, relay 146, the operat- 110 115 120 125 130

ing magnet 326 of the district switch 300, relay 417, the operating magnet 411 of switch 400 and the operating magnet 508 of the connector switch 500. The entire connection 5 through the switches is thereby released and the apparatus is thereby restored to its normal condition.

Selection of P. B. X. trunk on a different connector switch.

10 In the example above given it was assumed that the first idle P. B. X. trunk in the group was located in the same connector switch 500 with the identifying P. B. X. call-line 538. A portion of the trunks of this group, however, are illustrated on another connector switch 1300, and in case all trunks in the switch 500 are busy, one will be chosen on the other switch frame provided there is an idle one on such other frame at the time. Assume that the trunk 1324 is the first idle one of the group. The selecting circuit above traced may now be followed by way of conductor 1170, outer 20 right contact of relay 543, left front contacts of relays 550, 551 and 552, conductor 555, left front contact of relay 1326, left back contact of relay 1327, winding of the operating magnet 1309 to battery. Magnet 1309 25 operates, prepares the contacts in the vertical row 1321 and closes a circuit by way of conductor 1325, through the windings of relays 415 and 1247, in parallel to battery. Relay 415 closes a circuit for the vertical 30 operating magnet 407 which controls the row of contacts in the switch 400 representing trunks outgoing to the connector switch 1300. Relay 415 also associates the test relays of the marker with the sleeve conductors of these trunks. Magnet 407 brings 35 about the operation of relay 1121 in the manner above explained.

40 In a manner similar to that above explained, a test is made of the group of trunks outgoing from the selector switch 400 and providing trunk 428 is the first idle one, a circuit is established for the vertical operating magnet 1307 of the connector switch 1300.

45 Since the multi-contact relay 1247 and 1246 are operated in conjunction, a circuit is traceable over the grounded conductor 1171, through the inner right contact of relay 543, right front contacts of relays 550, 551 and 552, conductor 557, right front contact of relay 1326, right contact of relay 1327, conductor 1328, contacts of relays 1246 and 1247, conductor 558, winding of multi-contact of relay 1318 to battery. Relay 55 1318 operates and associates the test relays 1222, 1224 in the marker with the corresponding horizontal links 1304, 1305 and the horizontal magnets 1313, 1314 of the group having access to the idle trunk 1324. The 60 several conductors leading from the test re-

lays 1222, 1224, etc., are illustrated as multiplied to indicate that they are connected to the respective horizontal conductors in the device 1316 similar to the manner in which they are connected to the device 510 associated with the switch 500. After the necessary time interval has been measured, a circuit is closed for the horizontal magnets 411 and 1314 in the manner above explained and the connection is extended through the group 70 selector switch 400 and the connector switch 1300 to the idle P. B. X. trunk 1324. Following this, the marker is disassociated from the selector and connector switches as explained. 75

Extension of a connection to a direct subscriber's line.

80 The extension of a connection to an ordinary subscriber's line occurs in substantially 85 the same manner as that already explained in the connection with the selection of the P. B. X. call-line 538. In this case, however, the test made to determine the condition of the line is somewhat different from 90 the test of the idle P. B. X. trunks. Assume that a call is intended for the subscriber's line 535. Up to the point where the connector switch vertical magnets are operated 95 to select the line 535 the operations are substantially as above related. At the time relay 1137 operates following the operation of the vertical magnet 514, a circuit is closed from ground over conductor 1158, outer right back contact of relay 1159, outer contact of relay 1121, conductor 1162, left front contact of relay 1137, conductor 541, contact 100 of relay 513, winding of the horizontal test magnet 526 to battery. The magnet 526 prepares the testing link 509 which is common 105 to all links 507, 508, etc., in the group by connecting it to contacts of the vertical row 530 and contacts in the vertical row 532.

110 Subsequently, when the relay 1138 releases and while relay 1123 is still maintaining its armatures attracted, a test circuit is closed from battery through the winding of test relay 1122, left contact of relay 1123, outer left contact of relay 1138, middle right contact of relay 1130, outer right contact of relay 1129, the contacts of relay 416, sleeve conductor 425 of the trunk 422, thence over the test link 509 to the sleeve conductor 560 of the called subscriber's line. If the line 115 535 is idle, no ground occurs on the conductor 560, and consequently, relay 1122 remains deenergized. After an interval relay 1123 becomes deenergized and in the manner above explained, circuits are closed for the operation of the horizontal magnets 411 and 525 to extend the connection through 120 to the called subscriber's line 535.

125 If the called subscriber's line is busy, the test relay 1122 operates and locks to the grounded conductor 1141. Therefore, when 130

the relay 1123 subsequently released, the above traced circuits are not closed for the horizontal operating magnets and the connection is not extended through to the called line. Relay 1122, in operating, completes a circuit from the grounded conductor 1141, through its left contacts, conductor 1155, thence over conductor 1156, winding of the relay 750 to battery. Relay 750 locks 10 through its left contact to the grounded conductor 720. Relay 750 closes a circuit from ground through the secondary winding of the busy tone coil 751, inner right contact of relay 750, left hand winding of the balancing coil 701, condenser 741 to ground. Current flowing in this circuit induces a current in the right hand winding of the coil 701 which is transmitted to the calling substation 15 to produce a busy tone in the calling subscriber's receiver.

In the manner above described relay 1124 releases and operates the release relay 1119 which brings about a disconnection of the sender from the line marker. In this case, 25 however, relay 703 remains deenergized since the operating circuit therefor is opened at the outer back contact of relay 750. Consequently, the sender remains connected to the calling subscriber's line until he recognizes 30 the significance of the busy tone and hangs up his receiver.

Replacing his receiver the subscriber opens the circuit of relay 700, which as above described, brings about the release of the sender 35 and the sender connector switch 600. Following this, the line switch and the district selector switch are released in the manner explained.

What is claimed is:

40 1. The combination with a selective switch of a group of lines appearing in said switch, means for extending a connection to said switch, means for operating said switch to select said group of lines, means responsive 45 to the operation of said switch for releasing the same without releasing the extended connection, means for testing said lines to determine an idle one, and means for thereupon reoperating said switch to extend the 50 connection to the determined idle line.

2. The combination with a number of selecting switches, of a group of lines distributed to appear in a plurality of said switches, each line appearing in only one 55 switch, means for extending a connection in the direction of said switches, means for operating one of said switches to select said group of lines, means responsive to the operation of said switch for releasing the same 60 without releasing the extended connection, means for testing said lines to determine an idle one, and means effective after said test to cause the operation of the proper one of said switches to extend the connection to the 65 determined idle line.

3. In a telephone system, a selective switch, a group of trunks appearing in said switch, means for building up a connection to said switch, means for operating the switch to select said group of trunks, and 70 means for releasing a portion of the connection and for automatically reestablishing the same to select a particular trunk in said group.

4. In a telephone system, a selective 75 switch, a plurality of groups of lines appearing in said switch, a series of switches for extending a connection to said first mentioned switch, means for operating said first mentioned switch to select one of said groups of lines, and means for partly releasing the connection and for automatically re-establishing the same to select a particular line in the selected group.

5. In a telephone system, a selective 85 switch, a group of trunks appearing in said switch, switching means for extending a connection to said switch, means for operating said switch to select said group of trunks, means for determining an idle one of said 90 trunks, and means for releasing said switch and for automatically re-operating the same to extend the established connection to the determined idle trunk in said group.

6. In a telephone system, a number of 95 switches a group of lines distributed to appear in a plurality of said switches, means for extending a connection in the direction of said switches, means for operating one 100 of said switches to select said group of lines, means for partly releasing said connection and for automatically re-establishing the same to any line in the selected group.

7. In a telephone system, a number of selective switches, a group of lines distributed 105 to appear in a plurality of said switches, means for extending a connection in the direction of said switches, means for operating one of said switches to select said group of lines, means for releasing the operated switch without disturbing the extended connection and for operating the same or any other switch to select a particular line in said group.

8. In a telephone system, a number of selective switches, a plurality of groups of trunks, each group distributed to appear in a plurality of said switches, means for extending a connection in the direction of said switches, means for operating a particular 115 one of said switches to select one of said groups of trunks, means for determining the first idle trunk in the selected group, means for releasing the operated switch without disturbing the extended connection, and means for operating the particular switch in which appears the determined idle trunk to extend the established connection to such 120 trunk.

9. In a telephone system, a selective 125

switch, a group of lines appearing in said switch, a line separate from said group serving to identify the group, switching means for extending a connection to said switch, 5 means for operating the switch to select said identifying line, and means for releasing said switch without disturbing the extended connection and for re-operating the same to extend the established connection to one of 10 the lines in said group.

10. In a telephone system, a selective switch, a group of trunks appearing in said switch, a line, means for extending a connection from said line to the selective switch, 15 a recording mechanism arranged to receive a record from said line to control the selective switch to select said group of trunks, means responsive to the selection of said group for releasing the switch without disturbing the extended connection and for establishing an other record on said mecha- 20

nism, and means controlled by said mechanism for re-operating said switch to extend said connection to one of said trunks.

11. The combination with a selective 25 switch, of a group of trunks appearing in said switch, a subscriber's line appearing in said switch, means for extending a connection to said switch, means for operating said switch to select either the subscriber's line 30 or said group of trunks, means responsive to the operation of said switch when the group of trunks is selected for releasing said switch without releasing the extended connection, means for testing said trunks to determine an idle one, and means for reoperating said switch to extend the connection to the determined idle trunk. 35

In witness whereof, we hereunto subscribe our names this 25 day of April A. D., 1923. 40

SAMUEL B. WILLIAMS.
EDWARD E. HINRICHSEN.
